TOILET PAPER HOLDER

Herman K. Dupre, Seven Springs, Champion, Pa. 15622

Filed Apr. 27, 1973, Ser. No. 355,090

Term of patent 14 years

Int. Cl. D6—06

U.S. Cl. D6—97

Fig. 1

Fig. 2

Fig. 3

Fig. 4

Fig. 5

Fig. 6

FIG. 1 is a perspective view of the toilet paper holder showing my new design;

FIG. 2 is a top plan view thereof;

FIG. 3 is a front elevational view thereof;

FIG. 4 is an end elevational view thereof, the opposite end being a mirror image of the end shown;

FIG. 5 is a rear elevational view thereof; and

FIG. 6 is a bottom plan view thereof.

I claim:

The ornamental design for a toilet paper holder, as shown and described.
